(57) **CLAIM**

The ornamental design for a seed port for a bird feeder, as shown and described.

DESCRIPTION

FIG. 1 is a front perspective view of a seed port for a bird feeder embodying my new design.

FIG. 2 is a front view thereof;

FIG. 3 is a left side view of the seed port of FIG. 1, the right side being a mirror image thereof;

FIG. 4 top view thereof;

FIG. 5 is a bottom view thereof; and,

FIG. 6 is a back view thereof.
